UNITED STATES PATENT OFFICE.

WALTER J. REYNOLDS, OF PROVIDENCE, RHODE ISLAND.

COMPOUND FOR TREATING ROAD-SURFACES.

1,131,793.

Specification of Letters Patent. Patented Mar. 16, 1915.

No Drawing.

Application filed September 22, 1910. Serial No. 583,307.

To all whom it may concern:
Be it known that I, WALTER J. REYNOLDS, a citizen of the United States, residing at Providence, in the county of Providence and State of Rhode Island, have invented a new and useful Compound for Treating Road-Surfaces, of which the following is a specification.

This invention has reference to improvements in compounds for treating road surfaces, and its object is to provide a compound which may be applied to the surface of a dirt, macadamized, or like road-bed, and which will act to bind the surface particles together into a hard compact mass of a dustless, weather resisting character.

It is customary to use crude petroleum as a top dressing for dirt, macadamized, and other like roads as a dust preventative, and such material is commonly applied to the road-bed by means of a sprinkling cart, or other sprinkling apparatus. Crude petroleum, however, is lacking in adhesive qualities, and is not fully resistant to weather conditions so that under conditions of use the surface treated will at times flake off from the underlying portions of the road bed, and the petroleum will leach through the upper layers of the road-bed, so that its surfacing qualities are thereby lost. Again, crude petroleum is not sufficiently resistant to the action of rain to resist the washing effects of rain water, especially in the case of heavy rains, and extensive repairs are frequently demanded, even in a single season. The tendency of the crude petroleum to leave the surface of the road-bed detracts from the dust-laying qualities of such material, so that retreatment of the road is demanded at comparatively frequent intervals. However, crude petroleum has the advantage of initial cheapness, and other qualities, which makes its use upon road-beds advantageous.

By the present invention certain objectionable features of crude petroleum are eliminated, so that there is produced a road dressing or coating compound which may be readily applied to the road surface by means of a sprinkler or like apparatus, and when applied becomes strongly adhesive to the dust or dirt particles, whereby the surface of the road is compacted into a hard mass in which the applied compound retains its adhesive qualities for long periods of time, and is resistant to weather conditions, so that it

is not washed away during heavy rain storms and will not seep or leach through the lower layers of the road-bed away from the surface.

The improved road dressing comprises a compound of crude petroleum and crude rosin, the rosin being dissolved in the petroleum either rapidly by the aid of heat, or slowly by immersion in the petroleum. No fixed formula can be given, since the proportions of crude petroleum and rosin will vary in accordance with the character of the road-bed to be treated. It has been found in practice that one and a half pounds of dark, cheap rosin and three quarts and two gills of crude petroleum, making in all one gallon of the compound, will produce an average mixture. The rosin is melted by heat until quite thin and the crude petroleum is then added and stirred into the hot rosin, the heating and stirring being continued until the mass becomes quite hot, after which the mixture or compound may be drawn off and cooled. The rosin and oil so mixed will not afterward separate.

Instead of forming the compound in the manner just described, twelve ounces of the dark, cheap rosin may be added to three quarts and five gills of crude petroleum and permitted to stand in a suitable receptacle for ten or twelve days with occasional stirring. The oil dissolves the rosin and the mixture is thorough.

Where the compound is to be transported by railroad or by water, as, for instance, in tank cars or tank vessels, a suitable proportion of rosin may be added to the crude petroleum in the storage tanks and this will become dissolved and intermixed by the motion of the cars or vessels during the time of transportation, so that the compound is ready for use when delivered. When, however, it is necessary to make the compound for immediate use, the heating process is to be employed.

Compounds made by the formulas given may be thinned by the addition of crude petroleum to the extent of one, two, three or more gallons of crude petroleum to one gallon of the compound, the character of the surface to be treated determining the degree of thinning of the compound.

The rosin adds body to the crude petroleum at a negligible cost and produces a heavy, sticky oil, which though thin enough for use with a sprinkler, is sufficiently sticky

and gluey to unite the particles of dirt or sand or dust composing the surface of the road-bed, and because of the nature of the compound it will remain in engagement with such united particles for long periods of time, and because of its character will resist the action of rain. Since weather conditions do not affect the compound except very slowly, there is no disintegration of the surface to produce dust to be blown away by winds as occurs after a comparatively short time period on roads treated with crude petroleum alone, this being due to the fact that with the compound of the present invention there is no leaching of the compound and no washing of the same away from the surface of the road bed. Furthermore, the compound after application will pack very hard under the action of vehicles, so that the road-bed is harder and correspondingly better than a road-bed treated with crude petroleum or other like oils. The treated road-bed, furthermore, catches and retains dust which may reach it and will readily shed water. While the surface of the road-bed treated with the compound of the present invention is sufficiently adhesive to catch and retain dust, it will not adhere to vehicle wheels or automobile tires, and consequently is harmless to the tires and because of its non-adhering qualities the treated surface does not flake up under the action of passing vehicles.

Any kind of road-bed which is improved by treatment with crude petroleum is susceptible of treatment with the compound of the present invention with a resultant sur-

facing superior to that produced by crude petroleum, and from actual comparison under like conditions has lasting qualities 40 many times that of a road-bed treated with crude petroleum alone. Of course, two or more applications of the compound to the road-bed may be made, if needed. While the application of the compound has been 45 described with relation to road-beds, it may be used in connection with sidewalks, in which case it is advisable to level off the sidewalk with a rake, and then sprinkle or pour the compound thereover, after which 50 sand or gravel may be sprinkled on the treated walk and rolled with a small roller, repeating the treatment if necessary. A road-bed of a railway may be rendered dustless by sprinkling with the compound 55 diluted as needed with crude petroleum.

What is claimed is:—

A normally liquid compound for treating road surfaces, consisting solely of crude petroleum and rosin dissolved therein, the petroleum largely predominating and the amount of rosin being sufficient to make the compound sticky and resistant to weather conditions, whereby the compound is adhesive to dust and resistant to the washing 60 effects of water, and maintains such characteristics for long periods of time.

In testimony, that I claim the foregoing as my own, I have hereto affixed my signature in the presence of two witnesses.

WALTER J. REYNOLDS.
